UNITED STATES PATENT OFFICE.

JONATHAN STERN, OF SAVANNAH, GEORGIA.

DESIGN FOR THE BACK OF ENVELOPES.

* SPECIFICATION forming part of Design No. 18,414, dated June 26, 1888.

Application filed May 23, 1888. Serial No. 274,841. Term of patent 7 years.

To all whom it may concern:

Be it known that I, JONATHAN STERN, a citizen of the United States, residing at Savannah, in the county of Chatham and State of Georgia, have invented and produced a new and original Design for the Back of an Envelope, of which the following is a specification, reference being had to the accompanying drawings, forming a part thereof.

10 Figure 1 represents the back of a closed envelope, showing my complete design thereon. Fig. 2 is a like view showing the closing-flap lifted up.

15 The leading feature of my design consists in a series of vertical and horizontal lines, which, crossing each other at right angles, thereby compose quadrangular spaces or entablatures, said entablatures being surrounded by a quadrangular border consisting of plain lines in 20 parallel alignment with the upper and lower edges and the two side edges of the envelope where folded over. The border is located a slight distance away from the folded-over edges of the envelope, thus leaving a plain margin 25 outside of and surrounding said border.

25 A represents the horizontal lines, and B the vertical lines, of the outside frame or border, each in alignment with the respective folded-over edges a b of the envelope and a short distance therefrom, leaving outside thereof free 30 margins a' b' .

C represents horizontal lines parallel with the border-lines A, and D represents vertical lines parallel with the lines B of the border.

X represents the lower flap of the envelope, 35 which in practice is made adherent to the folded-over wings x' x .

W represents the upper or closing flap, which is left free and is closed when the envelope is intended for transmission.

40 It will be seen that one or more of the described lines, forming the border or the entablatures E, cross the edges of the respective flaps X W where overlying the wings x' x .

45 What I claim is—
The design for the back of an envelope, as herein shown and described, consisting of a quadrangular border composed of plain horizontal lines A and vertical lines B, outside of which is a marginal space, a' b' , said quadrangular border inclosing and surrounding a series of quadrangular entablatures, E, composed by horizontal lines C and vertical lines D crossing 50 each other at right angles, one or more of the described lines crossing the outer limiting lines of the juxtaposed edges of the wings x' x and flaps X W.

JONATHAN STERN.
